SELF-LEVELING, STORING, AND
DISPENSING APPARATUSCarl H. Larsen, Brooklyn, N. Y., assignor to Amer-
ican Machine & Foundry Company, a corpo-
ration of New Jersey

Application December 23, 1950, Serial No. 202,495

11 Claims. (Cl. 312—71)

1

This invention relates to self-leveling, storing and dispensing apparatus and particularly to improvements for guiding, raising and lowering the material supporting platform.

Due to the expense of manufacturing self-leveling, storing and dispensing apparatus, there have been many instances where the unit could have served very advantageously in storing and displaying merchandise but the cost of such a unit has rendered it prohibitive for such use since the profit for each item stored in the dispensing apparatus is very small it would not be economically sound to use elaborate equipment for this purpose. Another difficulty has been in the case where compression springs have been used they have occupied so much room when in their compressed condition that usable storage space was lost.

An object of this invention is to provide a storing and self-leveling apparatus which will be of simple design, of low manufacturing cost and will have improved display facilities.

Another object of this invention is to provide a spring support which will permit the spring to telescope when in collapsed condition and which will enable the calibrated characteristics of the spring to be maintained while undergoing contraction or expansion.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Fig. 1 is an isometric front elevation of the improved self-leveling, storing and dispensing apparatus,

Fig. 2 is a sectional plan view as seen through line 2—2 of Fig. 3,

Fig. 3 is a sectional side elevation of the improved self-leveling, storing and dispensing apparatus,

Fig. 4 is a sectional rear view of the same mechanism as seen from line 4—4 of Fig. 3.

Fig. 5 is a partial sectional side elevation illustrating a modified form of a calibrated mechanism for counterbalancing the material carrying platform when it is in expanded position.

Fig. 6 is a partial side elevation partly in section showing the same modified elevating mechanism in telescoped position.

This invention is particularly well suited for dispensing relatively light weight material such

2

as sanitary napkins, paper napkins and toilet tissues where it is necessary that the calibrating and supporting mechanism be very sensitive to slight changes in weight. The apparatus of course is equally adaptable for use in supporting articles of much greater weight.

The apparatus shown in Fig. 1 consists of a base 10, and an upright frame 12, which extends upwardly from one side of said base. The front and back sides of said upright 12 is enclosed by suitable materials such as sheet metal plates 14 and 16. The front plate 16 has an elongated slit 18 through which the platform supporting cantilever frame 20 extends. The upper end of the slit 18 forms a stop 21 which limits the extent to which the frame 20 can move upwardly.

A vertical post 22 is secured at the lower end to the base 10 by suitable means such as the flange 24 and is secured at its upper end to the top 26 of the upright 12. The platform frame 20 is connected to a carriage 28 having rollers 30, 32 and 34 which roll against the vertical post 22 when guiding and supporting the platform 20 for free up and down movement.

The cantilever platform supporting frame 20 is maintained in a horizontal position at all times due to the engagement of the rollers 30 and 34 with the post 22.

A suitable elongated flexible member such as sprocket chain 36 is secured to the carriage 28 at one end and the other end is secured to the upper end of the upright 12. The sprocket chain 36 passes over a sprocket 38 mounted on the upper end 26 of the upright 12 and passes under and around the sprocket 40. The sprocket 40 supports a U-shaped bracket 42 to which is connected one end of a calibrated tension spring 44. The other end of the calibrated tension spring is connected to an anchor 46 attached to the base 10. The calibrated spring is of such design that it extends and contracts at a rate which is directly proportional to the weight of the material supported on the frame 20 to thereby maintain the upper layer of material supported on the platform 23 at a substantially constant predetermined level.

Suitable projections 54 and 56, preferably made of non-friction material are mounted in the far corners of the material supporting platform 20 and engage with the vertical guide channels 58 attached to the corner posts 48 and 50. This arrangement prevents the carrier from coming in contact with the side walls of the self-leveling dispenser and thus assures free and easy vertical movement of the carrier. These bearings can be

made of any suitable material such as a ball bearing roller or a piece of plastic having a low friction surface. Since the projections 54 and 56 make contact inside of the U-shaped channels, one may add a lubricant to the channel without having it come in contact with the material being supported on the platform 23.

The upper ends of the corner posts 48 and 50 are connected to the upright frame 12 by suitable cross bars 55. These cross bars are wedge shaped 10 as shown in Figure 1 to guide the articles P towards the center of the stack as the platform 23 moves upwardly when being unloaded.

The corner posts 48 and 50 are provided with elongated channel strips 53 attached thereto to form channels to receive advertising literature 52 which it will be noted serves a dual purpose. This literature advertises the merchandise stored in the dispenser and simultaneously acts as an enclosure for the dispenser. This enclosure may be readily replaced to maintain the advertising literature in conformance with the current advertising programs of the concerns displaying and storing their merchandise in the dispenser. This construction also saves material, saves weight and results in a dispenser which is more economical to construct so that it is economically feasible to use such apparatus for storing low profit merchandise.

In Figs. 5 and 6, I have shown a modified form of my invention wherein a carrier 58 is raised and lowered a distance corresponding to the weight of the material supported thereon by a compression spring instead of a tension spring. While a single compression spring may be used 30 for this purpose, it may be desirable in some instances to have the springs occupy as little space as possible when compressed. This may be readily accomplished by using a plurality of compression springs arranged end to end such as 40 compression springs 60 and 62. The lower calibrated spring is supported on the base 64 and carries at its upper end a suitable spring support 65. This support may consist of S shaped hooks or may be in the form of an oval ring which hooks over the top of the lower spring 62 such as support 65 as shown in Figs. 5 and 6.

The lower end of spring 60 rests on this support 65 and the upper end engages with the carrier platform 58. When the spring is totally compressed as in Fig. 6, one spring telescopes inside of the other spring. In the embodiment used to illustrate the invention, I have shown the upper spring 60 to be of smaller size than the lower spring 62. If desired this arrangement could be reversed and the larger spring could be placed on top. This has the advantage that a minimum of space is occupied by the counterbalancing mechanism and thereby permits a sensitive calibrated spring to be used where vertical storage distance is at a premium. This is particularly important in such a unit as a freezing cabinet for storing frozen foods.

The base 64 has an upright 66 and a frame which is similar to the structure shown in Figs. 1 to 4. The carrier platform has a plurality of rollers 68, 70, 72 and 74 which ride on a vertical post 76 in the manner previously described. When the modified form of my invention is used in conjunction with a freezing cabinet the enclosure walls 78 are eliminated. On the other hand when the unit is used in the open the cardboard enclosure 78 will be inserted in place to keep the unit enclosed and at the same time provide means for locating advertising matter 75

in a place where it will be readily noticed by the public.

The invention above described may be carried in construction within the scope of the claims for the particular device selected to illustrate the invention is but one of many possible embodiments of the same. The invention, therefore, is not to be restricted to the precise details of the structure shown and described.

What is claimed is:

1. A self-leveling, storing and dispensing apparatus comprising, a rectangular base, an upright extending upwardly from one side of said base, corner posts extending upwardly from the opposite side of said base, connecting bars connecting the upper end of each of said corner posts with said upright, said bars being formed with a taper for deflecting articles coming in contact therewith towards the area between said bars, a material supporting platform, a vertical column extending from said base along the center of said upright, a carriage riding on said column and connected to said platform for maintaining said platform horizontal, permitting said platform to move freely up and down, a guide for maintaining said platform substantially free from lateral movement, and a calibrated spring for counterbalancing the weight of material supported on said material supporting platform to maintain the upper layer of material supported thereon at a constant level by lowering and raising said platform a distance corresponding with the weight of each increment and decrement added to and removed from the platform.

2. A self-leveling, storing and dispensing apparatus comprising, a rectangular base, an upright extending upwardly from one side of said base, corner posts extending upwardly from the opposite side of said base, connecting bars connecting the upper end of each of said corner posts with said upright, said bars being formed with a taper for deflecting articles coming in contact therewith towards the area between said bars, elongated channels extending along said uprights, corner posts and base for receiving flat sheets of material such as advertising posters to enclose said apparatus, a material supporting platform, a vertical column extending from said base along the center of said upright, a carriage riding on said column and connected to said platform for maintaining said platform horizontal while permitting said platform to move freely up and down, a guide for maintaining said platform substantially free from lateral movement, and a calibrated spring for counterbalancing the weight of material supported on said material supporting platform to maintain the upper layer of material supported thereon at a constant level by lowering and raising said platform a distance corresponding with the weight of each increment and decrement added to and removed from the platform.

3. A self-leveling, storing and dispensing apparatus comprising, a base, a cylindrical post extending upwardly from said base, a cantilever frame connected to said post by not less than three rollers engaging therewith at opposite sides and at vertically spaced points and at least two of said rollers being formed with concave surfaces to engage opposite sides of the post to maintain said platform at right angles to said post and free from tilting when it travels up and down, a calibrated tension spring secured to said base, a flexible member connected to said frame and passing over a pulley positioned adjacent the

upper end of said post and means interconnecting the free end of said calibrated spring with said flexible member to maintain pressure on said member which is proportional to the distance said platform is depressed by the weight of material supported thereon so as to maintain the top of the material supported thereon at a substantially constant level.

4. A self-leveling, storing and dispensing apparatus comprising a base, a cylindrical post extending upwardly from said base, a carriage having not less than three guide rollers which are horizontally and vertically spaced to travel up and down on opposite sides of and engaging said post at vertically spaced points on said post to maintain said carriage free from tilting, a platform extending laterally from the carriage riding on said post, vertical corner posts extending upwardly from said base adjacent the outward corners of said platform, a pulley mounted adjacent the upper end of said cylindrical post, an elongated flexible member connected at one end to said carriage and passing over said pulley and connecting the other end to an anchor adjacent said pulley, a floating pulley supported in a loop formed in said elongated flexible member intermediate said anchor and said first named pulley, a calibrated tension spring connected at one end to said base and at the other end to said floating pulley to counterbalance the weight of the material supported on said platform, means mounted at the other edges of said platform to engage with said corner posts as the carriage platform moves up and down to prevent the carriage and platform from rotating relative to the cylindrical post by engaging with said corner posts.

5. A self-leveling, storing and dispensing apparatus comprising a rectangular base, a center post extending upwardly from one side of said base, corner posts extending upwardly from the opposite side of said base, means interconnecting the upper end of said corner posts with each other and with the upper end of said center post, a material supporting platform having a carriage which rides on said post, said carriage having a plurality of rollers engaging said post on opposite sides and at vertically and laterally spaced points, to maintain said platform horizontal and free from tilting as it moves up and down, a calibrated tension spring connected at one end to the base, elongated flexible elements connecting the other end of said calibrated spring to said carriage to counterbalance material supported on said material supporting platform to thereby maintain the upper layer of the material supported thereon at a substantially constant predetermined elevation, and pins extending outwardly from the corners of said platform which are adjacent to said corner posts to prevent said platform from rotating around said center post by engaging with said corner posts when said carriage is moved up and down by said calibrated spring to maintain the top of the material supported on said platform at a constant level by counterbalancing the weight supported thereon.

6. A self-leveling, storing and dispensing apparatus comprising a base, a post extending upwardly from said base, a horizontal platform movable up and down in front of said post, a carriage connected to said platform, rollers connected to said platform and engaging the front, rear, and lateral sides of said post to positively maintain said platform free from tilting while moving up and down, guide members mounted on said platform and engaging with stationary

means for maintaining said platform free from horizontal movement relative to said cylindrical guide post, and a calibrated spring interconnected between said platform and said base for contracting and expanding a distance correlated with the weight of the material supported on said platform so as to maintain the upper layer of said material at a constant level with respect to said upright.

10 7. A self-leveling, storing and dispensing apparatus comprising a base, a flat wall extending upwardly from one side of said base, said wall having a slit extending vertically along the center of said upright, a vertical post positioned behind said slotted opening, a carriage, rollers mounted on said carriage and tracking on the front, rear, and sides of said post to maintain said platform free from tilting, a material supporting platform connected to and supported by said carriage for movement therewith up and down on said post, and a calibrated compression spring positioned between said platform and said base for counterbalancing material supported on said platform so as to lower and raise said platform a distance correlated with the weight of each increment and decrement of material added to and removed from that supported on the platform.

8. A self-leveling, storing and dispensing apparatus comprising, a base, a wall extending upwardly from one side of said base, said wall having a slit extending vertically along the center of said wall, a vertical post positioned behind said slotted opening, a carriage, rollers mounted on said carriage and tracking on the front, rear, and sides of said post to maintain said platform free from tilting, a material supporting platform connected to and supported by said carriage for movement therewith up and down on said post, and calibrated springs positioned between said platform and said base for counterbalancing material supported on said platform so as to lower and raise said platform a distance correlated with the weight of each increment and decrement of material added to and removed from that supported on the platform, said compression springs being formed with two different diameters to permit one compression spring to telescope inside of the other when said springs are compressed.

9. A self-leveling, storing, and dispensing apparatus comprising a base and a post extending upwardly from said base, a cantilever carriage platform, a plurality of wheels mounted on said carriage platform to engage said post at vertically spaced points as well as the front, rear, and sides of said post to maintain said carriage platform horizontal and free from tilting at all times when traveling up and down on said post, a calibrated spring interconnected between a stationary part of said apparatus and said carriage platform to counterbalance material supported on said carriage platform, and means for maintaining said carriage platform free from circular movement relative to said post when moving up and down.

10. A self-leveling, storing, and dispensing apparatus comprising, a rectangular base, a vertical post extending upwardly from one side of said base, corner posts extending upwardly from the opposite side of said base, a material supporting platform, a cantilever material supporting platform connected to said carriage and extending laterally beyond said carriage and post, a carriage, vertically spaced rollers mounted on said carriage and riding on the front, sides, and rear

of said post to maintain said platform horizontal and free from tilting while moving freely up and down on said post; means maintaining said platform substantially free from rotary movement around said post; and a calibrated spring for counterbalancing the weight of the material supported on said material supporting platform to maintain the upper layer of material supported at a constant level by lowering and raising said platform a distance corresponding with the weight of each increment and decrement added to and removed from the platform.

11. A self-leveling, storing, and dispensing apparatus comprising, a rectangular base, a post extending upwardly from one side of said base, corner posts extending upwardly from the opposite side of said base, elongated channels extending upwardly from said base for receiving flat sheets of material such as advertising posters to enclose said apparatus, a cantilever material supporting platform, a carriage supporting said platform, vertically spaced rollers mounted on said carriage to ride on the front, rear and sides of said post to maintain said platform free from

10

tilting while permitting said carriage and platform to move freely up and down, means for maintaining said platform substantially free from rotary movement about said post, and a calibrated spring for counterbalancing the weight of material supported on said platform to maintain the upper layer of material supported thereon at a constant level by lowering and raising said platform a distance corresponding with the weight of each increment and decrement added to and removed from the platform.
